UNITED STATES PATENT OFFICE.

ALFRED HARRY PIPER, OF WOLSTANTON, ENGLAND, ASSIGNOR TO EDWARD B. DICKINSON, OF NEW YORK, N. Y.

DESIGN FOR A PLATE OR SIMILAR ARTICLE.

50,430.

Specification for Design.

Patented Mar. 6, 1917.

Application filed January 8, 1917. Serial No. 141,332. Term of patent 3½ years.

To all whom it may concern:

Be it known that I, ALFRED HARRY PIPER, a subject of the King of England, and resident of Kingswood, Southlands avenue, Wolstanton, Staffordshire, England, have invented a new, original, and ornamental Design for a Plate or Similar Article, of which the following is a specification, reference be-

ing had to the accompanying drawing, forming part thereof, which drawing is a plan view of a plate or similar article illustrating my new design.

I claim:

The ornamental design for a plate or similar article, as shown.

ALFRED HARRY PIPER.
